UNITED STATES PATENT OFFICE.

GROVER F. BLAIR, OF FORT WAYNE, INDIANA, ASSIGNOR OF ONE-HALF TO ROLANDIS
A. BLAIR, OF FORT WAYNE, INDIANA.

TIE-SPACER.

1,117,127.

Specification of Letters Patent. Patented Nov. 10, 1914.

Application filed June 12, 1914. Serial No. 844,693.

To all whom it may concern:

Be it known that I, GROVER F. BLAIR, a citizen of the United States, residing at Fort Wayne, in the county of Allen and 5 State of Indiana, have invented new and useful Improvements in Tie-Spacers, of which the following is a specification.

My invention relates to tie spacers which are adapted to be attached to the lower side 10 or bottom of the rail, and which, when so attached, serve as a fulcrum for a lever by which lever a tie may be forced into proper position with respect to the next adjacent tie or ties.

15 Heretofore the common practice has been, when a new tie is being inserted to replace an old one, or a tie which has been removed for any purpose is being returned, to drive the same into position with a sledge. More 20 or less injury occurs to the tie by the above practice. Devices have been used tending to relieve the difficulties referred to, but so far as I am aware they are clamped to the top of the rail and extend over its tread so 25 that should one be overlooked by the workmen and remain on the rail, a train striking it would be derailed.

The object of my invention is to provide a device which is quickly attachable to the 30 bottom of a rail and when so attached furnishes a fixed fulcrum for a lever, but which is also readily removable from the rail.

Referring to the drawings, which illustrate the preferred form of my invention, 35 Figure 1 is a plan view of a device constructed according to my invention; Fig. 2 a side edge view of the same; Figs. 3 and 4 views on lines 3—3 and 4—4 respectively, of Fig. 2, and Fig. 5 a section of a rail with the device 40 attached thereto.

In the drawings the body 10 is made of a material having suitable strength. The central portion of the body is recessed, as 11, to receive the flange of a rail. The side 45 walls 12, 13 of the recess are parallel and are diagonal to the longitudinal axis or the length of the body. Substantially one-half of each wall, adjacent their bases, and commencing at the diagonally opposite ends of 50 the walls, is cut into to form diagonally opposite horizontal recesses or slots 14, 15, the inner walls of which are parallel and at right angles to the length of the body, the uncut portions 16, 17 of the walls above re- 55 cesses 14, 15 forming inwardly extending

flanges, which will project over the side edges of the rail flange and onto the top thereof, thereby supporting the device on the bottom of the rail. In the forward side edge of one end of body 10 is a recess 18 60 which serves to receive the bar or other implement by which the tie is to be moved and which will prevent the bar from slipping off the body.

In practice the device is made right and 65 left so that one of each may be attached to opposite rails, the recess 18 of each facing the tie to be moved.

The device is attached to the rail by placing it under the rail, and diagonally thereof 70 so that the edges of the flange of the rail will pass between walls 12 and 13 and permit the bottom wall of recess 11 to abut the lower surface of the rail. The device is then twisted or turned on the rail so that 75 the edges of the flange of the rail will enter the right angle recesses 14, 15 and pass under flanges 16, 17 of the body 10. The edges of the flange then abut the walls of the two recesses and when the bar is engaged in recess 18 and pressure is brought to bear upon the bar in driving the tie away from the spacer, the spacer will grip the rail all the more tightly; since the pressure exerted by the bar against the spacer is at one end 85 thereof and in the same direction in which the spacer was moved on the rail to engage its flanges 16, 17 on the top of the flange of the rail. It will be understood that two 90 spacers are required, one attached to one rail and the other to the opposite rail, the notched end of each spacer being preferably on the outside of the rail. The tie is then capable of being driven bodily into position.

Numerous modifications in the form and 95 arrangement of the several parts are possible, but, I believe all such to be within the scope of my invention.

What I claim is:

1. A device of the class described consisting of a body, two spaced parallel walls diagonally disposed on the body, said walls having in their opposing faces and at opposite ends thereof two horizontal recesses which are substantially at right angles to 105 the length of the body, and the body having a recess in its side edge near one end thereof.

2. A device of the class described consisting of a body having a recessed portion extending transversely across it, the opposite 110

walls of said recess being substantially parallel and extending diagonally with respect to the length of the body, each wall having a horizontal recess adjacent its base and extending at substantially a right angle to the length of the body, the said recesses being at opposite ends of the walls and the body having a recess in one side edge adjacent one end for the purposes described.

10 3. A device of the class described consisting of a body, two spaced parallel walls diagonally disposed upon the body and extending transversely thereof, each wall having a horizontal recess adjacent its base and

extending substantially one-half the length 15 of the wall and at a right angle to the length of the body, said recesses being situated in opposite ends of the walls and the body having a recess in its side edge adjacent one end for engaging a tool as de- 20 scribed.

In witness whereof I hereunto subscribe my name this 9th day of June, 1914.

GROVER F. BLAIR.
